UNITED STATES PATENT OFFICE.

WILLIAM WOLFE, OF EBENSBURG, PENNSYLVANIA.

MOUTHPIECE FOR HORMS.

Application filed December 28, 1928. Serial No. 157,585.

This invention relates to a mouthpiece for horns and has for an important object thereof the provision of a mouthpiece which may be conveniently transferred for use in horns of different sizes and particularly for interchangeable use upon a cornet and trumpet, as these instruments are interchangeably played.

It is extremely difficult for a horn player to obtain the best results when playing a horn unless the mouthpiece employed is properly constructed and properly constructed mouthpieces are relatively expensive and difficult to obtain. Since the socket receiving the mouthpiece of a trumpet and cornet are of different sizes and the trumpet mouthpiece is considerably longer than the cornet mouthpiece, it would be impossible to transfer a mouthpiece of the ordinary construction from a cornet to a trumpet. It is accordingly necessary that the player provide two mouthpieces and unless these mouthpieces are exact duplicates, great difficulty is experienced in changing from one to the other thereof. It is accordingly an important object of my invention to provide a structure such that a mouthpiece which will fit in a cornet may be effectively extended and enlarged, so that it may be employed in a trumpet.

A further object of the invention is to improve the structure of the mouthpiece so that the production of the high and low notes of the range of the instrument is facilitated and the playing otherwise generally made.

These and other objects I attain by the construction shown in the accompanying drawings, wherein for the purpose of illustration is shown a preferred embodiment of my invention and wherein:

Figure 1 is a side elevation of a mouthpiece constructed in accordance with my invention showing the mouthpiece section thereof engaged in the receiving bore of a cornet tube;

Figure 2 is a similar view showing a complete mouthpiece engaged in the tube of a trumpet;

Figure 3 is an enlarged longitudinal sectional view through the mouthpiece;

Figure 4 is an end elevation thereof.

In accordance with my invention, the mouthpiece is formed in two separable sections 10 and 11, of which the section 10 con-

stitutes the actual mouthpiece and is provided with a mouthpiece bell 12 and with a tapered portion 13 of a size to properly fit within the mouthpiece receiving end of a cornet tube 14. The rim of the bell 12 is slightly rounded, as at 15, at its lip engaging surface and from this rim, the walls of the bore of the bell converge inwardly toward the throat 16 with very slight curvature, as indicated at 17. The outer face of the bell is concavely curved, as at 18, so that the wall of this bell, in advance of the throat, is relatively thin, this combination of curvatures for these surfaces having been found to produce a much clearer note in the use of the mouthpiece and to enable the production of high and low notes of the register with great ease. The throat 16 is preferably about five thirty-seconds of an inch in diameter and from this throat to the smaller end of the mouthpiece, the bore increases constantly in diameter, as indicated at 19, so that the wall of the smaller end of the mouthpiece at its free end is very thin.

The section 11 has a bore, the outer end 20 of which is constructed to receive and closely fit upon the smaller end of the mouthpiece, while the outer end of this bore is relatively straight, as indicated at 21. The exterior of the section 11 is slightly tapered, so that it will fit the mouthpiece receiving bore at the end of a trumpet tube 22 in such manner as to provide the necessary prolongation of the mouthpiece 10 when combined therewith. The section 11, if desired, may be left in the bore of the trumpet and the mouthpiece 10 simply removed therefrom and inserted in the cornet when the cornet is to be played. The player is thus free from the difficulties usually arising from the change of mouthpieces and is enabled to employ a mouthpiece giving the greatest efficiency to his instruments all the time.

Since the construction hereinbefore set forth is capable of a certain range of change and modification without materially departing from the spirit of the invention, I do not limit myself to such specific structure except as hereinafter claimed.

I claim:

A pipe section for converting the type of instruments of analogous character consisting of a sleeve section having an exterior surface tapered longitudinally and provided

with an internal bore having at one end a tapered surface, the taperings of the said surfaces being of the same pitch whereby a mouthpiece having exterior dimensions corresponding with the dimensions of the exterior surface of the sleeve may fit snugly within the tapered surface of the internal bore, and the other end of the interior bore having a cylindrical surface of the same diameter as the major diameter of the bore of the mouthpiece.

In testimony whereof I hereunto affix my signature.

WILLIAM WOLFE.
